(57) **CLAIM**

The ornamental design for an assistant tool for wearing socks, as shown and described.

DESCRIPTION

FIG. 1 is a front perspective view of an assistant tool for wearing socks, showing my design.

FIG. 2 is rear perspective view according to FIG. 1.

FIG. 3 is a front elevation view according to FIG. 1.

FIG. 4 is a rear elevation view according to FIG. 1.

FIG. 5 is a left side elevation view according to FIG. 1.

FIG. 6 is a right side elevation view according to FIG. 1.

FIG. 7 is a top plan view according to FIG. 1.

FIG. 8 is a bottom plan view according to FIG. 1; and,

FIG. 9 is an enlarged view of an area labeled 9 in FIG. 1. The broken lines depict environmental structure that forms no part of the claimed design to be patented.
